UNITED STATES PATENT OFFICE.

HALLECK J. DE LONG, OF CLEVELAND, OHIO.

VALVED FLUE.

1,165,946.

Specification of Letters Patent.

Patented Dec. 28, 1915.

Application filed June 1, 1915. Serial No. 31,610.

To all whom it may concern:

Be it known that I, HALLECK J. DE LONG, a citizen of the United States of America, residing at Cleveland, in the county of Cuyahoga and State of Ohio, have invented certain new and useful Improvements in Valved Flues; and I hereby declare the following to be a full, clear, and exact description of the invention, such as will enable others skilled in the art to which it pertains to make and use the same.

This invention relates to improvements in valved flues, and more especially to a valved flue adapted to conduct gases from a blast-furnace.

One object of this invention is to have said flue comprise not only two flue-sections which are arranged in line and spaced endwise and participate in the formation of a passageway for conducting fluids, but to have said flue provided with a rotary disk-valve adapted to control communication and arranged between said flue-sections and operatively connected with a suitably rotated shaft arranged externally of the flue.

Another object is to have said valve supported externally of the aforesaid passageway so that the bearing of the valve is not exposed directly to fluid conducted through the passageway.

Another object is to have adjacent end-portions of the aforesaid flue-sections contoured as required to permit the use of a valve which is not objectionably large in diameter.

Another object is to provide improved means for establishing a tight joint between the valve and said flue-sections in either position of the valve and for loosening said valve relative to said flue-sections preparatory to the actuation of the valve from one to the other of its positions.

Another object is to render my improved valved flue simple and durable in construction.

With these objects in view, and to the end of attaining any other advantage hereinafter appearing, this invention consists in certain features of construction, and combinations and arrangement of parts, herein-after described, pointed out in the claims and illustrated in the accompanying drawings.

In said drawings, Figure 1 is a horizontal section of a portion of a valved flue embody-

ing my invention, and in this figure the valve is shown in its open position. Fig. 2 is a side view of said flue. Fig. 3 is a vertical section on line 3—3, Fig. 2, looking in the direction indicated by the arrow. Fig. 4 is a vertical section on line 4—4, Fig. 3, looking in the direction indicated by the arrow. Fig. 4 is drawn on a larger scale than Figs. 1, 2 and 3 which are drawn on the same scale.

My improved fluid-conducting flue comprises two tubular metal sections A and B which are shown arranged horizontally and in line endwise, and 6 indicates the adjacent end-portions of said flue-sections. Said end-portions of the flue-sections extend into proximity to each other at their adjacent ends, but are spaced far enough apart endwise at said ends to permit the interposition between them of a rotary disk-valve C employed in controlling communication between said flue-sections, and said valve consists preferably of a circular metal plate provided at its periphery with gear-teeth 7 so as to form a combined gear and valve. The valve C therefore extends between and faces adjacent ends of the flue-sections A and B but has such dimensions relative to said ends of said flue-sections that its periphery and its axis are arranged externally of the passageway formed within and by said flue-sections.

Preferably each end-portion 6 of each flue-section has its bottom sloping upwardly, as at 8, Figs. 2 and 3, in the direction of the valve and has its sides diverging in said direction, as at 10, Fig. 1. The sloping of the bottoms of adjacent end-portions 6 of the flue-sections upwardly and toward the valve permits the use of a valve which is considerably smaller in diameter than would be necessary if the flue-sections were not thus reduced in size vertically at their adjacent ends, and the divergence of the sides of said end-portions of the flue-sections toward the valve is not unimportant in that the lateral enlargement thereby attained of said end-portions is essential to substantially avoid reduction in the fluid-conducting capacity of said end-portions of the flue-sections by the reduction in size vertically of said end-portions.

Preferably adjacent end-portions 6 of the flue-sections A and B are provided externally at the faces of the valve with metal clamping members 12 which extend around

or circumferentially of and are riveted or otherwise secured to the flue-sections.

Preferably the valve C is loosely mounted on a horizontal pin D which is arranged 5 longitudinally of the flue and below and externally of the passageway formed in and by the flue-sections A and B. The pin D is supported from the clamping member 12 of the end-portion 6 of the flue-section A and 10 extends, as shown in Fig. 4, through said clamping member and longitudinally of said flue-section, and the valve is therefore supported from said clamping member and consequently from said flue-section. It will 15 be observed that the clamping member 12 of the flue-section A is arranged at one face of the valve and that the clamping member 12 of the end-portion 6 of the flue-section B is arranged at the other face of the valve, 20 and that the valve is adapted to be clamped at its faces by and between said clamping members as will hereinafter more clearly appear. By my improved construction the pin D is unexposed to the action of any fluid 25 passing through the flue.

The valve is provided between its axis and its periphery with a port 13 extending through the valve from face to face of the valve and having a wall 14 which (see Fig. 30 3) extends circumferentially of said axis a distance somewhat less than half way around said axis and having another wall 15 which extends between the ends of the first-mentioned wall, and it will be observed 35 that adjacent ends of the end-ports 6 of the flue-sections substantially correspond in contour with the outline of the valve-port 13, and that said port is arranged wholly above the axis of the valve in the open position of the valve, as shown in Figs. 3 and 40 4, but obviously the valve has been actuated into its closed position and communication between the flue-sections A and B is interrupted upon the rotation of the valve, when 45 the valve is free to rotate, far enough in either direction until said opening is in position below said axis.

The end-portion 6 of the flue-section B is provided externally with two brackets 16 50 arranged at opposite sides respectively of said flue-section, and the flue-section A is provided externally with two brackets 17 arranged at opposite sides respectively of said flue-section.

Two screws E are arranged at opposite 55 sides respectively and externally of the end-portion 6 of the flue-section A, which screws are in line endwise transversely of said flue-section. Onto each screw E is screwed a spur-gear G which supports said screw and 60 is supported from the adjacent bracket 17, and said bracket is contoured as required to permit endwise movement of said screw during the rotation of said gear, and means 65 for preventing movement of said gear end-

wise of said screw are provided and comprise a shoulder 18 formed internally of said bracket at one end of the hub of the gear and a cross-bar 19 with which said bracket is provided at the other end of said 70 hub.

Each screw E is operatively connected at its outer end by a link e with the adjacent ends of the two links K of a toggle-joint which is arranged longitudinally of the flue and extends between and is connected to the adjacent brackets 16 and 17 of the flue-sections A and B. One link of said toggle-joint is shown pivoted vertically at its outer end, as at 20, to the adjacent bracket 16 of the flue-section B, and the 80 other link of said toggle-joint is shown pivoted vertically at its outer end, as at 21, to the adjacent bracket 17 of the flue-section A. The screw E at one side of the flue is right-handed and the screw E at the other 85 side of the flue is left-handed, so that when the gears G are simultaneously rotated in the same direction said screws are simultaneously shifted endwise but in opposite directions respectively. When the valve C is 90

clamped by and between the clamping members 12 of the flue-sections A and B the links K of each toggle-joint are somewhat out of line, as shown in Fig. 1, and obviously upon the shifting of the screws E endwise in the 95 direction required to move said links into line said flue-sections are separated slightly farther than shown in Fig. 1 and consequently loosened relative to the valve C. Obviously when the valve C is clamped by 100 and between the clamping members 12 of the flue-sections A and B the joints between the valve and said flue sections are substantially fluid-tight, and the valve must be loosened relative to the flue-sections before 105 actuating the valve from one to the other of its positions.

Under the sloping bottom of the end-portion 6 of the flue-section A is located a shaft L which is arranged horizontally and transversely of said flue-section and supported from the brackets 17. The shaft L is parallel with the screws E and extends under said screws. The shaft L is operatively provided under each screw E with a pinion 110 7 which meshes with an intermediate gear 22 supported from the adjacent bracket 17 and meshing with the gear G engaging said screw, and said shaft is operatively provided at one end thereof with a sprocket 115 23 which is actuated by a suitably applied and suitably driven chain 24. It will be observed therefore that the shaft L is intergeared with the screws E, and that said screws are actuated endwise toward or from each other according as said shaft is rotated in the one direction or the other, and that consequently the toggle-joints are 120 simultaneously operated to cause the valve 125 to be clamped by and between or rendered 130

loose relative to the opposing faces of the clamping members of the flue-sections according as said shaft is rotated in the one or the other direction.

5 At the outer side of one of the brackets 17 is arranged a shaft R which is arranged horizontally and parallel with the axis of the valve C and (see Fig. 2) has bearing in a box 25 formed on said bracket, and said 10 shaft extends into suitable proximity to the periphery of the valve and is operatively provided with a pinion r which meshes with the gear formed by the toothed peripheral portion of the valve. It will be observed 15 therefore that the shaft R is intergeared with the valve. The shaft R is also operatively provided with a bevel-gear 26 which meshes with a bevel-gear 27 operatively mounted on a shaft T which is arranged 20 horizontally at the outer side of and at a right angle to and intergeared with the pinion-bearing shaft R and supported from an arm 28 of the adjacent bracket 17 and operatively provided at its outer end with 25 a sprocket-wheel t driven by a suitably applied and suitably actuated chain 29.

By the construction and relative arrangement of parts hereinbefore described it will be observed that the valve has its gear-forming peripheral portion extending outwardly beyond the flue-sections all around the latter and exposed to the atmosphere externally of the flue-sections, and that the shaft R and its pinion r and the shaft T 30 are also arranged wholly externally of the flue-sections and exposed to said atmosphere, and consequently said shafts, said pinion and the valve are not overheated by hot 35 gases or fluid conducted through said flue-sections.

What I claim is:—

1. The combination, with two flue-sections participating in the formation of a fluid-conducting passageway and spaced endwise, of a suitably supported rotary disk-valve arranged between and facing adjacent ends of said flue-sections, which valve is provided between its axis and its periphery with a port arranged to establish communication between said flue-sections in the open position of the valve, said port having a wall extending circumferentially of said axis and having another wall extending between the ends of the first-mentioned wall, and said flue-sections substantially corresponding in contour at their adjacent extremities with the outline of said port in the open position of the valve.

2. The combination, with two flue-sections participating in the formation of a fluid-conducting passageway and spaced endwise, of a suitably supported rotary disk-valve arranged between and facing adjacent ends of said flue-sections, which valve 50 controls communication between said flue-

sections and has such dimensions relative to said ends of the flue-sections that its periphery is arranged externally of the aforesaid passageway and its axis is arranged below and spaced from said passageway, adjacent 70 end-portions of said flue-sections having their bottoms sloping upwardly in the direction of the valve and having their sides diverging in said direction.

3. The combination, with two flue-sections 75 participating in the formation of a fluid-conducting passageway and spaced endwise, a suitably supported rotary disk-valve arranged between and facing adjacent ends of and controlling communication between 80 said flue-sections, said valve having a toothed peripheral portion which forms a gear and extends outwardly beyond said flue-sections, and a bracket arranged at one side and externally of and rigid with one 85 flue-section, of a shaft supported from said bracket and arranged longitudinally of said flue-section and extending into proximity to the periphery of the valve and operatively provided with a pinion which is in mesh 90 with the gear-forming peripheral portion of the valve, and a suitably driven shaft supported from said bracket and arranged at the outer side of and at an angle to and intergeared with the first-mentioned shaft. 95

4. In a valved flue, the combination with 100 two flue-sections participating in the formation of a fluid-conducting passageway and spaced endwise, and a suitably supported disk-valve arranged between and facing adjacent 105 ends of said flue-sections and controlling communication between the flue-sections, each flue-section being externally provided at the adjacent face of the valve with a clamping member which extends circumferentially of said flue-section, of suitably operated toggle-joints arranged externally of the flue, each toggle-joint having one link thereof connected to one of the flue-sections and its other link connected to the other 110 flue-section.

5. In a valved flue, the combination, with 115 two flue-sections participating in the formation of a fluid-conducting passageway and spaced endwise, and a disk-valve adapted to control communication and arranged between said flue-sections, the flue-sections being externally provided at the faces of the valve with clamping members extending circumferentially of the flue-sections, of a shaft 120 arranged externally of the flue, and toggle-joints arranged externally and longitudinally of the flue, each toggle-joint having one link thereof connected to one flue-section and its other link connected to the other 125 flue-section, and such an operative connection between each toggle-joint and the aforesaid shaft that the flue-sections are relatively positioned to cause the valve to be clamped by and between or rendered loose 130

relative to the clamping members of the flue-sections according as the shaft is retained in the one or the other direction.

6. The combination, with two flue-sections 5 participating in the formation of a fluid-conducting passageway and spaced endwise, and a disk-valve arranged and controlling communication between said flue-sections, the flue-sections being externally provided at 10 the faces of the valve with clamping members extending circumferentially of the flue-sections, of two screws arranged externally of opposite portions respectively of one flue-section, one screw being right-handed and 15 the other left-handed, gears screwed onto said screws and supported from said flue-section, means for preventing movement of the gears endwise of the screws, a shaft intergeared with said gears, and toggle-joints 20 arranged adjacent the outer ends of and operatively connected with the screws, one link of each toggle-joint being connected to one flue-section and the other link of said toggle-joint being connected to the other flue-section, and the screws being adapted to 25 move endwise during the rotation of the aforesaid gears.

7. The combination, with two flue-sections

participating in the formation of a fluid-conducting passageway and spaced endwise, and a disk-valve arranged and controlling communication between said flue-sections, adjacent end-portions of the flue-sections having their bottoms sloping upwardly in the direction of the valve and their sides 35 diverging in said direction, of a shaft arranged under the sloping bottom of the valve-facing end-portion of one flue-section, toggle-joints arranged longitudinally and externally of the flue-sections, each toggle-joint having one link thereof connected to one flue-section and its other link connected to the other flue-section, and means whereby the toggle-joints are simultaneously actuated to cause the valve to be clamped by and 40 between or rendered loose relative to the clamping members of the flue-sections according as the aforesaid shaft is rotated in the one or the other direction.

In testimony whereof, I sign the foregoing specification, in the presence of two witnesses.

HALLECK J. DE LONG.
